MARKING DEVICE FOR ROAD SURFACES

Ernest Lewis Gethin, Morden, and George Douglas Worthington, New Malden, England

Application October 31, 1938, Serial No. 237,874
In Great Britain March 15, 1937

6 Claims. (Cl. 94—1.5)

This invention relates to methods of and means for surfacing road and like prepared surfaces and is more particularly concerned with methods of and means for marking such surfaces as required for instance in connection with the demarcation of traffic lanes, signal stop lines, pedestrian crossings and boundary lines on roadways and the boundary and other lines of the playing courts employed in tennis, fives and other games.

One object of the invention is to provide an improved and simplified form of marking device which is both cheap and easy to install and is durable.

Another object of the invention is to provide a method of producing distinctive markings on a road or like surface by laying a strip of rubber or rubber-like substance with an upper surface to form the desired marking in the material of the said surface and anchoring such strip by embedding a plurality of dependent portions formed integral therewith in surrounding material of the road or like surface.

A further object of the invention is to provide a strip of rubber or rubber-like substance for the purpose of surfacing or marking a road or like surface which comprises a cap portion whose upper surface forms the desired marking and dependent locking portions integral with said cap portion for embedding in the material of the road or like surface.

Yet a further object of the invention is to provide an improved and easily visible device of rubber or like resilient substance suitable for marking the kerb or boundary of a road or like surface and which is securely anchored in position by embedding dependent portions thereof in the material of the associated surfaces on either side of the said device.

A number of constructional embodiments of the invention will now be described with reference to the accompanying drawings, wherein:

Fig. 1 is a perspective view of one form of marking device according to the present invention;

Fig. 2 is a cross-sectional view of the embodiment shown in Fig. 1 when in position in a road or like surface;

Fig. 3 is a cross-sectional view similar to Fig. 2 showing a slightly modified formation;

Fig. 4 is a cross-sectional view, similar to Fig. 3, showing a further modified construction;

Fig. 5 is a perspective view of the construction shown in Fig. 1, modified to form a stud-like marking element;

Fig. 6 is a perspective view, similar to Fig. 5, of a slightly modified form of stud-like element;

Fig. 7 is a cross-sectional view taken on the line VII—VII of the embodiment shown in Fig. 6;

Fig. 8 is a perspective view of a further form of the invention, of particular application to a road surface having a deep top-surface layer, such as a wood-paved or cobbled surface or where the requirements of usage call for a deeply grouted unit;

Fig. 9 is a cross-sectional view of the embodiment shown in Fig. 8 when in position in a road or like surface;

Fig. 10 is a perspective view of a further modified form of the invention, of particular application to the formation of kerbing for a roadway;

Fig. 11 is a cross-sectional view of the embodiment shown in Fig. 10;

Fig. 12 is a schematic perspective view illustrating yet a further form of surfacing or marking device according to the present invention and showing the various steps involved in laying the device to form a marking line in an existing road or like surface;

Fig. 13 is a cross-sectional view of a modified form of the strip shown in Fig. 12;

Fig. 14 is a perspective view of a further embodiment of the invention showing the application thereof to a rubber-faced paving block;

Fig. 15 is a cross-sectional view of a slightly modified form of the block shown in Fig. 14; while

Fig. 16 is a perspective view of a modified form of kerbing construction.

Referring first to the embodiment shown in Figs. 1 and 2 it will be seen that the member which gives the desired marking line or other symbol consists of a strip 10 made of rubber or similar resilient rubber-like material. The strip 10 comprises a top cap-part 11 whose uppermost surface 12 is the one adapted to give the desired indication in the road or other surface and for this reason is given a distinctive colour enabling it to contrast with the colour of the surface in which it is laid. Extending downwardly from each lateral edge of the top cap-part 11 are side walls 13 which are provided at their lower ends with outwardly extending flanges 14. The outer edge of each of the flanges 14 may be provided with an upstanding rib 15 as shown while each flange may also be provided with a number of apertures 16 which assist in anchoring the

device in position in a manner hereinafter described.

The inner surfaces of the top cap-part 11 and the side walls 13 define a recess 17 which serves to receive a core 18 of comparatively cheap and preferably rigid material such as wood or a bituminous mixture or the like, for instance a composite mixture of bituminous compound and sawdust. The outer surfaces of each side wall 13 are preferably arranged as shown to present an undercut construction and are preferably grooved or ribbed in a longitudinal direction of the strip 10 as indicated at 19. The flanges 14 preferably taper in cross-section from their junction with the side walls 13 to their free extremities as shown.

As indicated in Fig. 2, the strip 10 is laid in position upon a prepared foundation 20 with the core 18 disposed within the recess 17. The top-dressing or carpet 21 of the road or like surface is then built up over the flanges 14 so as to lie substantially flush with the top surface 12 of the strip 10. The material of the carpet 21 (e. g. tar-macadam in the case of a road surface) enters into engagement with the undercut and preferably ribbed side walls 13 and the flanges 14 so that the device is firmly anchored in position. The presence of the ribs 15 and the apertures 16 serve to increase the anchoring effect of the carpet material 21 on the device. If necessary the carpet material adjacent the edges of the strip may be consolidated with the aid of additional binding material such as bitumen compound or tar. It will be clear that instead of laying the strip 10 and core 18 upon a separately prepared foundation, a channel of suitable width and depth may be routed out of an existing finished surface, the device laid therein and then anchored by filling the remaining spaces of the 40 channel with a suitable surfacing material (such as tar-macadam or a bituminous compound).

Fig. 3 shows a slightly modified version of the construction of Figs. 1 and 2. In the perviously described embodiment the inner surfaces of the 45 side walls 13 were flat and disposed at right-angles to the under-surface of the top cap-part 11 so that the core 18 could assume a plain rectangular cross-section when properly fitted within the recess 17. In the example shown in Fig. 3, however, the coherence between the strip 10 and the core 18 is increased by making the inner surfaces of the walls 13 convex as shown at 22 to engage with correspondingly-shaped side faces 23 of the core so that the latter will be firmly held 50 in engagement with the strip when it is placed in position (e. g. by sliding-in lengthwise) in the recess 17. Alternatively, the side walls of the core 18 could be convex and the inner faces of the side walls 13 concave. In the embodiment 55 shown in Fig. 3 the ribs 15 along the free edge of each of the flanges 14 are omitted, the flanges tapering to a feather edge, but it will be clear that such ribs may be provided or alternatively they may be omitted, in similar manner, from 60 the form shown in Figs. 1 and 2. In other respects the two embodiments are substantially identical and similar reference numerals indicate like parts therein. In either case the flanges 14 may be ribbed longitudinally in similar manner 65 to that shown at 19 in Fig. 1.

The uppermost or marking surface 12 of the strip 10 may be flat but is preferably slightly convex as shown in order to increase its visibility. If desired it may be made even more conspicuous 70 by increasing the degree of curvature as shown

at 24 in Fig. 4. In this case the rigid core 18 is preferably replaced by core members 25 of yieldable material such as sponge rubber. The members 25 are formed as strips disposed adjacent each side wall 13 and forming between them a cavity 26. Such a construction allows the strip 10 to yield and be squeezed downwardly so as to bring the top surface 24 more or less flush with the surface of the adjacent carpet 21 when a load, such as a passing vehicle, is applied thereto. 10

The strip 10 in each of the above described embodiments is formed as a one-piece or integral member of rubber or like material and while such member may be formed in any suitable manner known in the art of rubber goods manufacture it 15 is preferred that the member 10 be formed as a continuous strip by an extrusion method. In such case the apertures 16 may be punched or cut-out either before or subsequent to curing of the extruded strip. The formation of the mem- 20 ber 10 in strip-form allows of economical production since any desired length of marking device within practical manufacturing limits can be cut-off as required.

In the case where marking devices of very short 25 length are required, for instance to form studs as are frequently employed instead of continuous lines for traffic marking purposes, the arrangement shown in Figs. 5, 6 and 7 may be used. In this construction a short-length member 10a is 30 provided. Such member may be cut from a continuous strip 10 formed as previously described. This form is shown in Fig. 5. Alternatively such member may be formed individually, for instance by moulding, in which case it will preferably take the form shown in Fig. 6 with its top surface 12a slightly convex in both longitudinal and trans- 35 verse directions. The member 10a is provided with a length of rubber-impregnated canvas- 40 sheet or like material 27 vulcanised or otherwise securely fixed to the underside of the top cap- part 11a thereof. The overhanging end pieces 28 of this sheet constitute anchoring means which are additional to the flanges 14, side walls 13 and other associated features similar to the corre- 45 spondingly numbered parts of Figs. 1 to 3. In the mounting of such a stud element, a suitable core 18a (Fig. 7) is inserted within the recess 17a defined by the side walls 13 and the ends 28 of the 50 canvas-sheet are then turned outwardly so as to lie upon the prepared foundation 20 and thus to constitute additional anchoring flanges so that the stud is anchored on all four sides when the top-surfacing or carpet material 21 is built up 55 around the stud. In a further alternative form of the arrangement shown in Fig. 6 the member 10a may be formed with outwardly projecting integral flanges 14 on all four sides.

Figs. 8 and 9 show a modified form of the construction shown in Figs. 1 and 2 particularly suitable for use where the top-surface layer of the road or like surface is of considerable depth, such, for instance, as a road surface paved with wood-blocks or cobblestones or where the requirements of usage call for a deeply grouted unit. In this embodiment the side walls 13b of the member 10b are suitably extended, being preferably slightly undercut as shown and ribbed longitudinally while the core 18b is suitably increased 70 in dimensions to occupy the enlarged recess 17b. In mounting such a form of marking device it is placed as before upon the prepared foundation 20 (Fig. 9) and the blocks 29 constituting the top-surface are arranged to overlie the flanges 14b, 75

the blocks being suitably recessed for this purpose if necessary. One form of recessing is shown on the left-hand side of Fig. 9 and an alternative arrangement in which a positive interlock between the surface block and the ribbed flange of the strip is obtained, on the right-hand side of that figure. The various spaces between the blocks 29 and the member 10b are filled with a suitable binding material such as a bituminous compound 30. To increase the anchorage of the member 10b, apertures 16b may be provided as before in the flanges 14b while perforations 31 may be formed in the side walls 13b for the reception of the said binding material in order to increase the security of fixing of the device.

The embodiment above described in connection with Figs. 8 and 9 is also applicable for mounting in an all-concrete road, the device being laid upon the hard-core foundation and the concrete road material being built up around it to the desired level in the usual manner.

Figs. 10 and 11 illustrate a modification of the invention suitable for forming an easily visible kerbing for roadways, paths and other surfaces. In this construction a member 32 of rubber or similar rubber-like material has a top-part 33 whose uppermost surface 34 forms a horizontal marking surface and two integral dependent side walls 35, 36 disposed one on each of the lateral sides of the top-part 33. The side wall 35 is relatively short and is provided with an outwardly projecting flange 37 similar to the flanges 14 of the embodiment shown in Fig. 1. This side wall is preferably undercut as in the previous embodiment and is also grooved or ribbed as at 38 throughout its depth. The other wall 36 is of greater depth than the wall 35 and is also provided with an outwardly projecting flange 37 at its lower end. The lower region of this wall is preferably grooved or ribbed at 39 in similar manner to the wall 36. Each of the flanges 37 may be provided with marginal ribs 40 and apertures 41 in similar manner to the arrangement shown in Figs. 1 and 2.

In the mounting of this embodiment a core 42 of rigid material such as timber is disposed within in the channel-like recess formed between the side walls 35, 36 and top cap-part 33 and the assembly laid in place upon the foundation 43 of the road or like surface. The top dressing or carpet material 44 of the road or like surface is then built up over the flange 37 and against the side wall 36 so as to cover the ribbed or grooved part 39.

The foundation 45 of the part which is to form the raised pathway is built up on the opposite side of the core 42 to the level of the under-surface of the flange 37 of the side wall 35. Top-dressing 46 such as asphalt applied on top of the foundation 45 is built up over the flange 37 and against the side wall 35 to anchor the member 32 on this side in similar manner to that effected on the roadway side.

In order to increase the visibility at night of the kerbing thus formed suitable reflector devices such as the prismatic glass reflectors indicated at 47 may be mounted in the side wall 36 of the member 32. Such reflector members may be held in suitable apertures formed in the side wall or in an alternative construction they may be located within suitable recesses formed in the core and arranged to project through apertures in the side wall 36. In order to protect such reflectors from the effect of impact with the wheels of passing vehicles they may be backed with a pad

of sponge-rubber or the like or if desired the top edge of the wall 36 may be provided with an overhanging lip. In each of the embodiments above described a core member has been employed. This core member may, if desired, be made of sufficient depth to be partially embedded in the foundation material of the road in order to give increased resistance to movement. As already indicated in normal circumstances, with the exception of the arrangement of Fig. 4, such core is of rigid and preferably cheap material, for instance it may be of creosoted timber, earthenware, concrete or bituminous composition. Alternatively, however, it may be made of the same material and integral with the rubber or rubber-like body whose upper surface forms the desired indication. In a further alternative construction the side wall parts and/or the anchoring flanges need not be integral with the top cap or marking portion but may be secured thereto. For instance in the case of marking strips they may be formed as strips of canvas impregnated with rubber and attached to the top cap-part in a suitable way for instance by vulcanising in similar manner to the strips 27 of the stud-like elements of Figs. 5 and 6.

Fig. 12 illustrates a further and simplified form of the invention. This embodiment makes use of a strip-like member 50 of rubber or rubber-like substance consisting of a top cap-portion 51 the uppermost surface 52 of which is adapted to form the desired indicating surface. This top portion is provided with a number of downwardly projecting integral tongues 53 and 54 which are shaped to lock with the material of or associated with the prepared surface whereby the entire member is secured in position. The tongues 54 are formed so as to have a progressively increasing width in a downward direction so that they assume a "dovetail" cross-section while the tongues 53 which are located adjacent the side edges of the strip are of "half-dovetail" cross-section, each having an outer wall substantially at right angles to the top surface 52 and an inner wall which diverges inwardly as shown. The outer wall surfaces of the tongues 53 and the integral side edges of the top cap-part 51 are preferably grooved or ribbed as indicated at 55 for assisting in the anchoring of the member in similar manner to the other embodiments.

The mounting of this embodiment is conveniently effected as follows when it is to be placed in position in a road or like surface which is already prepared. A channel 56 of a depth and width slightly greater than the corresponding dimensions of the strip 50 is routed out of the prepared surface 58. Into this channel is next introduced a quantity of settable binding material 57 such as a hot bituminous compound. The strip 50 is then placed in the channel on top of the binding material and worked in such manner that the latter enters the dovetail grooves formed between the various tongues 53, 54. The final position of the strip 50 is such that the top surface 52 is either flush with or projects slightly above the adjacent road or like surface. A further quantity of the binding material 57 may then be introduced between each side edge of the strip 50 and the adjacent edge of the channel 56, the combined setting and adhesive qualities of the binding material acting in conjunction with the tongues 53, 54 and ribbed side surfaces 55 serving to anchor the strip firmly in position.

This last-mentioned form of the invention is particularly suitable for forming stud-like ele-

ments similar to those shown in Figs. 5 and 6. Such an element is constituted by simply cutting off a suitable length from a strip of material of the form shown and is anchored in similar manner to that described in connection with Fig. 12. As in the case of the previous embodiments the strip 50 is preferably formed of rubber or like material by an extrusion method but it may be formed in other known and suitable ways. The form of the device shown in Fig. 12 is also applicable to the surfacing of roads and the like. The various strips necessary to cover the desired area may be anchored in place in the manner previously indicated by the use of a suitable binding agent or alternatively they may be set in cement or concrete in somewhat similar manner.

A slightly modified form of the embodiment shown in Fig. 12 is illustrated in Fig. 13. In this example the strip 50a which is of the same shape as the strip 50 of Fig. 12 is provided on its lower surface and its two side edges with a layer 57b of bitumen. The bitumen layer is provided upon the strip during manufacture and the process of laying merely involves the unwrapping of the prepared strip and its securing in desired position with the aid of a further small amount of hot bitumen which combines with the bitumen layer of the strip and engages the interstices of the surrounding surface material.

30 In order to increase the security of anchoring of each end of a strip or stud formed according to the arrangement of Figs. 12 or 13, plugs as shown at 54a (Fig. 12) may be inserted in the undercut grooves formed between the tongues 53, 35 54. These plugs are shaped according to the contour of the grooves and, if left partially projecting from each end of the strip, form additional anchoring lugs to be embedded in the carpet or binding material subsequently applied around the strip. They also serve to prevent the escape of bituminous material trapped within the interior of the grooves during the laying process. Such plugs may also be used as joining two strip portions together in which case they serve to align 40 and anchor the two parts.

45 The form of each of the embodiments already described is such that they may readily be distorted to accommodate themselves to a wide variety of positions for instance to the camber of a 50 road, the curvature of a corner of a road and even to the curvature necessary to form various alphabetical letters for incorporation in a road surface in the form of a traffic sign such as the word "stop" or "slow."

55 Fig. 14 illustrates a further modified form of the invention. In this construction a strip of rubber or rubber-like material is provided with a top cap-member 60 and a downwardly extending tongue 61 for keying engagement with material 60 of the road or like surface. This tongue is, for instance, adapted to fit within a shaped recess 62 in a base block 63 forming part of a road structure. The base block may be of suitable material such as iron, concrete or earthenware. The parts 65 61 and 62 are arranged to interlock with one another being shaped for example as shown with each part undercut. Preferably the interlocking parts are so arranged that the block 63 may be fixed in place separately and the top cap 60 applied thereto afterwards. Such application may be made by laterally compressing the resilient top-part during insertion of the tongue 61 within the recess 62, whereupon the subsequent release will allow the tongue to expand and grip the recess to anchor the parts together. Such a con-

struction permits the removal of the top-cap when worn and replacement by a new part of different thickness. Alternatively the top cap may be slid into position lengthwise. The upper or bearing surface may be provided with grooves 64 5 for anti-slipping and drainage purposes.

The top surface of the cap-part 60 may be rounded or domed as shown at 65 in Fig. 15 and in another slightly modified form the bottom of the tongue 61 is arranged normally to be out of 10 engagement with the bottom of the co-operating recess 62. In this construction the application of a load upon the top surface of the cap 60 first causes deformation of the cap until the bottom of the tongue contacts with the recess whereupon 15 its resistance to further depression is increased.

The shape of the base block shown in Fig. 14 is suitable for a paving block where similar blocks are laid side by side. In the case where the combined base block and rubber facing strip is to be 20 inserted in a road or like surface to form an indication or marking the side faces of the block are preferably recessed as shown at 66 (Fig. 15) in order to allow proper keying of such blocks in 25 position.

In order to improve the non-slipping properties of the rubber members as described in connection with Figs. 14 and 15 the top cap-part may be made slightly smaller than the base block as shown in Fig. 15. In this way, when a number 30 of similar blocks are laid side by side a small space 67 will be left between each.

The rubber cap-part 60 in each of Figs. 14 and 15 is preferably formed as in the previous embodiments by extruding a continuous strip and cutting the latter into suitable lengths. Instead of fitting the strip 60 into blocks it may be laid directly in the road surface being secured in place by being embedded in concrete, tar-macadam or 40 the like.

Fig. 16 shows a modified form of kerbing similar in general features to the embodiments of Figs. 14 and 15. In this arrangement a core or base block 70 is partially embraced by a rubber layer 71 the top surface 72 of which forms the 45 horizontal surface of the kerb and the vertical face 73 the road facing side of the kerb. The member 71 is provided adjacent each longitudinal edge with an inwardly facing locking tongue 74, preferably of undercut form as shown, which engage within correspondingly shaped recesses 75 in the core block 70. To assist in the retention of the tongues 74 within the grooves 75 the rubber layer member 71 may be given such an initial 50 form that the side walls carrying the tongues are inclined inwardly towards each other and so tend to maintain the tongues in proper position.

When laid in position upon the road foundation 76 the lower edges of the layer member 71, which are ribbed as shown at 79, are overlapped or covered by the surfacing material 77 and 78 of the roadway and pathway respectively so that the tongues 74 are effectively held in proper position.

If desired, reflecting plates and like devices may be mounted in the side wall 73 in similar manner to that already described in connection with Figs. 10 and 11.

In order to increase the visibility at night of the various marking elements previously described, the rubber or rubber-like material from which they are constructed may have powdered pumice or ground glass incorporated therein.

We claim:

1. A marking stud for road and like surfaces comprising a portion of required length cut from a strip of rubber having a cap-part with an upper surface for forming the required marking and dependent side walls along each longitudinal edge of said cap-part and outwardly projecting flanges at the lower marginal edges of said side walls, a strip of rubberized fabric material of longer length than the cut-off length of the strip-portion secured to the underside of said cap-part and overhanging each end of said cut-off portion and a core of rigid material of dimensions to fit beneath said cap-part.
- 15 2. A marking device for road and like surfaces comprising a substantially rectangular core of rigid material and an elongated covering member of extruded resilient material of uniform composition such as rubber partially surrounding said core, said covering member comprising a top-cap part covering the upper surface of said core and having an upper surface adapted to form the required marking, two dependent side walls integral with said top-cap portion and extending downwardly from opposite lateral side edges of the latter to cover opposite side surfaces of the core, and outwardly directed flanges integral with the lower extremities of each of said side walls each of said flanges being provided 25 with a raised rib along its free edge.
- 30 3. A marking device for road and like surfaces comprising a rigid core and also an elongated covering member of extruded rubber of uniform composition partially surrounding said core, said covering member comprising a top-cap part covering an upwardly facing surface of said core, two dependent side walls integral with said top-cap part and extending downwardly on

opposite sides of said core and means integral with the lower extremities of each of said side walls for locking them in position upon said core and in the surrounding surface.

4. A marking device for road and like surfaces comprising an elongated one-piece strip-like extruded body of material of uniform composition such as rubber having a top-cap part, dependent side walls integral with said top-cap portion and extending downwardly from each lateral side 10 edge of the top-cap part, and means upon each of said side walls for anchoring their lower extremities within the material of the surface on both sides of the device.

5. A marking device for road and like surfaces comprising in combination a substantially rectangular core of rigid material and an elongated covering member of extruded material of uniform composition such as rubber partially surrounding said core, said covering member 20 comprising a top-cap part covering the top surface of said core, a side wall integral with said top-cap part covering substantially the whole depth of one side surface of said core, a second side wall integral with the top-cap part and of 25 less depth than the first-mentioned side wall and covering only a part of the total depth of the opposite side surface of said core and outwardly directed flanges at the lower extremities of each of said side walls for embedding in the 30 material of the surface on either side of the device.

6. A marking device for road and like surfaces as claimed in claim 5 comprising reflecting devices embedded in the first-mentioned side. 35

ERNEST LEWIS GETHIN.
GEORGE DOUGLAS WORTHINGTON.
